COMMUNICATION AND SIGNALING SYSTEM

Harry H. Stockfeld, Washington, D. C.

Application August 8, 1938, Serial No. 223,761

5 Claims. (Cl. 177—353)

This invention relates to control means for signaling devices employed in conjunction with communication systems. More particularly, the invention relates to improved control circuits for audible and visual indicating devices which are operated in combination with communication systems of the type in which transmitted electrical impulses serve selectively to actuate type bars of printing machines.

One of the inadequacies in modern business practices is the lack of timely knowledge resulting from inadequate modes of communication between producers of goods and consumers or their agents. In order to foster economic distribution of goods and produce it is necessary that substantially all of the potential purchasers not only be in continual communication with each other but also at the same time be in communication with the producers. The communications systems which have heretofore been known which were designed to facilitate the continual exchange of information between each of the various trading centers of this country and the producers of goods and produce have been highly complicated, expensive, subject to errors of the human element and difficult to maintain on a timely basis. In part this has been caused by the large number of trading or auction centers which must be served by the system and the additional fact that producers, especially of farm produce, are frequently located in remote sections of the country.

With the foregoing in mind it is an object of this invention to provide an improved communication and signaling system suitable for transmitting and receiving information in a timely and accurate manner between many widely separated stations such as would be necessary to enable sales to be negotiated by auctions or similar modes of business wherein the traders are located at remote points from each other.

Another object of this invention is to provide an improved communication system of the type in which electrical impulses are set up which serve to actuate in a selective manner particular type bars of a plurality of printing machines located in the system and the operation of said system serves to control signaling circuits embodying signaling devices.

Another object of this invention is to provide an improved communication system having a plurality of stations at each of which a sequence of signal actuation is attained by operation of the communication system mechanism located at that station whereby the user of the system at a

particular station may govern his use of the communication system.

Another object of this invention is to provide an improved control circuit for signaling devices which is actuated by either a transmitting device or a receiving device or both located in a communication system of the teletypewriter type.

A still further object of this invention is to provide an improved control circuit for audible and visible signaling devices wherein the devices operate in response to a sequence of relay operations initiated by an instrument of a teletypewriter communication system.

It is a further object of this invention to provide an improved communication system of the teletypewriter type embodying signaling means at each of a plurality of stations operating in response to a sequence of relay actuations which is simple in design and which serves as a means for timely and accurately exchanging information between a large number of users of the communication system.

Other objects, features and advantages will become apparent as the following detailed description of the improved communication and signaling system is explained, reference being made to the drawings wherein:

Fig. 1 is a schematic diagram in block form disclosing a plurality of stations of the improved communication and signaling system;

Fig. 2 is an across the line wiring diagram of a preferred form of the improved control circuit for the signaling system;

Fig. 3 is a perspective of a manually actuated electrical impulse controlling device in the form of a key lever provided with a contactor device;

Fig. 4 is a detailed showing of the contactor device appearing in Fig. 3; and

Fig. 5 is a side elevation of a contactor device adapted to be actuated by a member moving in accordance with a selected pull bar of a teletypewriter printing device.

Figure 6 is a schematic diagram disclosing a plurality of stations and the contactors which serve to actuate the associated signal stations.

As shown in Fig. 1 the communication and signaling system contemplates a plurality of teletypewriter stations each containing transmitting and receiving units which are electrically connected together for simultaneous reception of messages from one of the stations in the group during operation of its transmitting unit. As shown by the figure, each of the stations has associated therewith a signal station, the operation of which is controlled by movement of an

element of the transmitting or receiving device during its normal operation, as will be explained in later passages. From the standpoint of this invention, the number of stations in the communication system is immaterial although it is necessary that all of the stations be equipped for reception of impulses impressed upon the main teletypewriter circuit which connects the stations together as well as for transmission to the receiving or printing units located in the remaining teletypewriter stations connected to the chain. Inasmuch as the teletypewriter devices and circuits per se are known in the art, a detailed description is unnecessary although the elements associated with the system which coact with the signal system to form the improved combination will hereinafter be explained in detail.

The control circuit for the signaling system which is employed at each of the signal stations associated with each of the teletypewriter stations disclosed in Fig. 1 is shown in detail in Fig. 2. In this figure, conductors L₁ and L₂ represent a local source of electrical energy at the signal station. The devices contained in the control circuit comprise a master contactor 10 having contacts 11 and 12 and a contactor 53 positioned in shunt relation to master contactor 10. Reference numeral 13 represents a sustaining contactor which has contacts 14 and 15 and numeral 54 represents a contactor located in shunt relation to sustaining contactor 13. A multiple contactor relay which is generally represented by numeral 16 comprises an operating coil 17 having associated therewith an armature mechanically connected to operate contact bridging members 18, 20 and 22. Three sets of contacts which have been designated 19, 21 and 23 are positioned to be bridged during operation of the relay. Reference numeral 24 represents a time delay relay of a type which may be accurately adjusted to operate after a delayed period of relatively short duration. The operating coil 50 of the time delay relay 24 is energized from conductors L₁—L₂ upon the closure of contactor 54 or upon closure of sustaining contactor 13 or upon bridging of contacts 19 by member 18. Energization of the operating coil 50 of time delay relay 24 serves instantly to close the contacts of the relay. Upon deenergization of the operating coil of the time delay relay, a predetermined time elapses before the armature is released to open the circuit between L₁ and contacts 21. Means (not shown) are provided for adjusting the relay to vary the elapse of time between the deenergization of the operating coil and the opening of the relays.

The signal devices are represented by reference numerals 32 and 33. The former represents a lamp suitable for indicating a visual signal to a large group of people. Numeral 33 represents an audible signaling device such as a bell and preferably the bell employed in the circuit is of the single stroke type, i. e., actuation of the bell will result in a single stroke of the clapper against the gong.

Master contactor 10 together with contactor 53 and coil 17 of the multiple contactor relay 16 are connected in series in line 40 which connects across the energizing circuit L₁ and L₂. Contacts 19 are connected in conductor 42 which forms a parallel path with conductor 43 between point 44 and the side of the circuit designated L₁ in which sustaining contactor 13 and contactor 54 are located. The energizing coil 50 of time delay relay 24 is connected between point 44 and the side L₂ of the energizing circuit by conductor

45. Contacts 46 which are closed by bridging member 47 of relay 24 are located in series with contacts 21 in conductor 41 which connects with line 40 at point 48 at one end of the conductor and with side L₁ of the energizing circuit. In this manner a parallel circuit is established between L₁ and point 48 in one side of which contacts 11 and 12 are located and in the other side of which contacts 21 and 46 are located. Signaling devices 32 and 33 are located in a branch circuit one side of which connects with L₂ and the other side connects through contacts 23 and conductor 49 with L₁ of the energizing circuit. It is manifest that the signaling devices might be connected in series depending upon the character of the devices or an additional number or different types of devices could be employed without departing from the spirit of the invention.

The operation of the control circuit for the signaling devices is as follows: During a de-energized condition of the operating coil 17 of multiple contactor relay 16, contacts 19 of the relay 16 are closed by member 18, and contacts 21 and 23 are open as shown in Fig. 2. Contacts 46 of the time delay relay 24 are normally open when circuit L₁—L₂ is de-energized. Upon energizing circuit L₁—L₂ from a source of potential at the local signaling station the operating coil 50 of time delay relay 24 is energized causing the relay to pick up and instantaneously close contacts 46 by bridging member 47. The circuit by which the coil is energized extends from line L₁, conductor 42, contacts 19 to point 44, coil 50 and conductor 45 to L₂. After energization of circuit L₁—L₂ the control circuit is in condition for operation in conjunction with teletypewriter station with which it is associated.

Master contact 10 is adapted for the momentary closing of contacts 11 and 12 and when this is done coil 17 of the multiple contactor relay 16 is energized which results in opening contacts 19 and closing contacts 21 and 23. Opening of contacts 19 serves to interrupt the energizing potential for coil 50 of the time delay relay 24. It is apparent that any of the various types of instantaneous closing, time delay opening relays which may be accurately adjusted for relatively short periods of time may be employed and are contemplated in this invention, such, for example, as relays which employ thermionic tubes and operate on the condenser discharge principle. The closing of contacts 21 serves to close a circuit from L₁, conductor 52, contacts 46, contacts 21, conductor 41, through coil 17 of multiple contactor 16 to L₂ which locks the multiple contact relay in its operated position. When relay 16 is in its operated position contacts 23 are closed which completes a circuit from L₁ through conductor 49, contacts 23, signaling devices 32 and 33 to L₂. Thus upon the momentary closure of contactor 10 or its associated contactor 53, the multiple contactor relay 16 is operated to energize an interlocking circuit which continues the energization of coil 17 as long as contacts 46 are closed and also to energize the circuit in which the visual and audible signaling devices are located. As long as relay 16 remains energized, light 32 will be lighted and upon initial energization the bell which has been described as a single stroke type will be sounded. It is contemplated that other types of signaling devices such as annunciators and the like may be employed in circuit L₁, conductor 49, contacts 23 and L₂ without departing from the scope of this invention.

Upon energizing coil 17 and operation of multi-

ple contactor relay 16 the circuit of the coil of relay 24 is interrupted by opening of contacts 19. After a delay of a predetermined time, as explained above, relay 24 will allow the armature to be moved which will result in opening of contacts 46. This will interrupt the interlocking circuit of coil 17 comprising L₁, conductor 52, contacts 46, contacts 21, conductor 41, operating coil 17, to L₂ and thus de-energize relay 16 to cause interruption of energy to the signaling devices 32 and 33. The momentary closure of sustaining contactor 13 or its associated contactor 54 prior to the de-energizing of multiple contactor relay 16 serves to re-energize coil 50 of time delay 24 through circuit L₁, conductor 43, contacts 14, 15, point 44, coil 50 of relay 24, conductor 45 to line L₂. Energizing of the operating coil 50 in this manner will recondition relay 24 and reset the time delay period. In this manner the operation of the signaling devices may be sustained for an indefinite period by repeatedly closing sustaining contactor 13 or contactor 54 within any of the time delay periods provided contactor 13 or contactor 54 is momentarily operated prior to the interruption of the interlocking circuit of coil 17 by opening of contacts 21.

Mechanical interconnection between the control circuit for the signaling devices and the teletypewriter communication system is accomplished by employing moving elements of the teletypewriter transmitting and printing units to operate the master contactor 10 and sustaining contactor 13 as well as their associated contactors 53 and 54. This result is achieved by placing the contactors relative to particular moving elements of the teletypewriter units so that mechanical motion will be transmitted from the moving element to the movable element of the contactors whereby the contacts will be momentarily closed in accordance with the operation of the communication system. As illustrative of the interconnection between the signal system and a transmitter of a teletypewriter unit employed in each of the stations, reference is made to Figs. 3 and 4 which disclose a teletypewriter key lever 60 of the type conventionally employed in teletypewriter units for manual actuation of the transmitting unit. Key lever 60 is pivoted on a bar 61 which is supported in a known manner and is spring biased to its raised position by means of spring 62. A surface 63 is provided on the opposite end of the lever from the point at which it is pivoted which serves as an engaging means for the fingers of the operator. Inasmuch as the structure of the key lever is well known a further description is unnecessary. In addition to the control of a particular character such as a letter or a symbol in the teletypewriter communication system, the key also serves to actuate contactor 64 which is schematically shown in Fig. 2 as the master contactor 10 or sustaining contactor 13 depending upon the particular key lever by which it is actuated. Any type of contactor may be employed which is adapted to be momentarily closed by the depression of the key lever 60 during the normal operation of the teletypewriter transmitting unit. By way of illustration, reference is made to the details of a contactor in Fig. 4 which may be employed for this purpose. The particular contactor disclosed in Fig. 4 embodies a yoke and connecting link 65 which is pivotally secured to the key lever 60 by use of a screw and bolt 66. The yoke and connecting link 65

5 is preferably insulated from the key lever by the use of an insulating collar 74. The shank portion of the yoke and connecting link 65 is adapted to move a conducting member 67 through a lost motion connection which comprises spring 68 and washers 69 and a friction engagement between member 67 and link 65. Contacts 70 are located on the lower side of conducting member 67 which are adapted to coact with contacts 71 located on an insulating base 72. Depression of the key lever 60 serves to force contacts 70 and 71 into engagement whereby an electrical circuit is closed between conductors 73. Guide members 75 formed of insulating material are provided for conducting member 67 in order to insure accurate engagement of contacts 70 and 71. By virtue of the spring 68, the yoke and connecting link 65 is allowed additional downward motion over that necessary to close the contacts. Thus contacts 70 and 71 are maintained in contacting relation by virtue of the pressure exerted by spring 68 when key lever 60 is depressed through a portion of its stroke. It will be evident that the operation of a key controlling a particular character or symbol on the teletypewriter transmitting unit will serve not only to send an impulse over the communication system which will energize a corresponding character on the printing units of the various teletypewriter receivers in the system, but will also serve to initiate the control circuit for the signaling devices in the local signal station which is associated with the particular transmitting unit. Fig. 5 discloses a contactor which is adapted to be controlled by a moving element of a teletypewriter receiving or printing unit. The contactor comprises contacts 80 which are mounted on conducting spring members 81. The conducting spring members are secured on an insulating base 82 and are equipped with binding posts 83 to which the conductor leads are attached. An insulating strip 84 is positioned beneath the lower conducting spring member 81 in order that the control circuit for the signaling devices in which the contactor is employed will be insulated from the moving member of the teletypewriter printing unit. A pull bar which serves to actuate a type bar of any given character in the teletypewriter printing unit is shown in Fig. 5 as the means for actuating the contacts 80. The pull bar is of the type conventionally used in teletypewriter printing units and neither it nor its actuating mechanism form a part of this invention. It is contemplated that other moving elements, such as the type bar, of a particular character may be adapted to control a contactor without departing from the spirit of this invention. The contactor disclosed in Fig. 5 is schematically shown in Fig. 2 as the contactors 53 and 54 which are located in circuits which bridge across master contactor 10 and sustaining contactor 13. It is apparent that when an electrical impulse is received by the teletypewriter printing unit which causes the pull bar of a particular character or symbol to be raised, the contacts 80 will be closed.

Reference is made to Figure 6 for a more complete description of the communication and signaling system. Reference numerals 90, 91 and 92 schematically represent teletypewriter stations each of which comprise transmitting contacts 93 and receiver magnets 94. Station circuits 95 are interconnected by a network represented by reference numeral 96. Each of the teletypewriter stations 90, 91 and 92 have associated

therewith a signal station represented by reference numerals 97, 98 and 99, respectively. Contactor 10 of Figure 2 which is shown in detail in Figures 3 and 4 is actuated in each of the teletypewriter stations by depressing a character key. For purposes of explanation the key may be considered as the X character key. Sustaining contactor 13 of Figure 2 which is similar in detail with contactor 10 is provided to be actuated by another character key, which for purposes of explanation may be considered as the Y character key. Contactor 10 and sustaining contactor 13 of each of the associated signal stations are actuated by the X and Y character keys in each of the teletypewriter stations. Contactor 53 of Figure 2 which is shown in detail in Figure 5 is actuated in each of the stations by a pull bar of the receiving unit. While the contactor may be actuated by any of the pull bars, for purposes of explanation, it will be considered that contactor 53 is actuated by the pull bar corresponding to the character X. Contactor 54 of Figure 2 is similar in detail to that of 53 and it is actuated by a pull bar different from that which actuates contactor 53. For purpose of explanation it may be considered that contactor 54 in each of the stations is actuated by the pull bar corresponding to character Y. Contactor 53 and contactor 54 of each of the associated signal systems are actuated by the pull bars corresponding to characters X and Y, respectively, in each of the teletypewriter stations in the system.

From the description of the control circuit and arrangement of contactor parts it becomes apparent that operation of a designated key lever on a transmitting unit will serve to close master contactor 10, shown in Fig. 2, which in turn will initiate the operation of the control circuit and cause the signal device to operate. In addition, it will serve to initiate an electrical impulse which will cause corresponding type bars having the same characters or symbols of printing units in all of the stations connected in the communication circuit to be operated. Operation of the type bars in the printing units will result in the closure of the multiple contactor relay operating coil in each of the stations thus initiating their signal circuits. From the description thus far given it will be apparent that depression of a key lever corresponding to a particular character such, for example, as the character X, will result in the simultaneous initiation of the control circuits for the signaling devices in both the transmitting station and each of the receiving stations. Likewise depression in either the same or a different station of a different key lever corresponding to a different character or symbol, such for example, as the character Y will result in simultaneously conditioning the control circuits of the signal devices in both the sending station and each of the receiving stations to sustain the signaling devices in operation.

In order to obtain a complete understanding of the operation of the communication system and the signal circuit operating in conjunction with each station of the system, the operation will be explained in connection with the simultaneous auctioning of goods or produce in a plurality of trading centers. Prior to the simultaneous opening of the bidding in the various trading centers a description of the goods together with designating nomenclature is transmitted over the communication system from each of the various stations whereat the goods are offered for sale, so that information concerning the goods is

available at all of the stations in the communication system. At a designated time an operator at one of the teletypewriter stations which, for example, may be assumed to be station No. 1 will strike a particular key such, for example, as the key corresponding to character X on the transmitting unit in that station. This will cause master contactor 10 in station No. 1 to be closed thus actuating the signal circuit in this station. 5 In addition, the X type bars of the receiving units at stations No. 2 and 3 will be operated in accordance with the operation of the conventional teletypewriter system and contactor 53 in each of the signal circuits of stations No. 2 and 3 will be closed by movement of the respective pull bars in the receiving units. In this manner the signaling circuits of stations No. 2 and 3 will be simultaneously initiated with the signal circuit of station No. 1 to close the circuits of the signaling devices in each of stations No. 1, 2 and 3. 10 As long as contacts 46 are closed the signaling devices will remain energized in each of the stations although after energization of multiple contactor relay 16 in each of the stations, coil 50 15 of the time delay 24 is deenergized thus starting the period at the end of which contacts 46 are opened.

While the local signaling circuits of each of the stations are in this condition, buyers at the 20 various stations may transmit their bids over the teletypewriter system in sequence as the transmission channels become open due to the cessation of transmission of a previous bid. Transmission of the bids will be made prior to the opening of contacts 46 and to insure that the contacts will remain closed during the bidding period, a key such, for example as the Y character key will be pressed by the operator of the transmitting teletypewriter unit at the termination 25 of the transmission of each bid. Pressing of the key corresponding to the character Y will serve to close contactor 64 associated with the key which corresponds to sustaining contactor 13 in Fig. 2 as explained above. Assuming that 30 a bid is transmitted from station No. 3 after which the operator strikes character key Y, the key movement will serve to close sustaining contactor 13 in station No. 3 which will cause the time delay relay 24 to be conditioned for another period of time before opening of contacts 46 in station No. 3. The striking of the Y character key in station No. 3 will result in transmission of impulses over the teletypewriter system and the type bars corresponding to character Y in each 35 of the printers at stations No. 1 and 2 will be actuated. Resulting movement of the pull bars of the printers will serve to close contactors 54 in each of stations No. 1 and 2 which in turn will result in reconditioning the respective time delay 40 relays in the signaling circuits of stations No. 1 and 2 for an additional period of time. Upon the cessation of transmission of bids a definite time will elapse due to the operation of the time delay relay before the signaling devices will become deenergized. Upon the de-energization of the signaling devices in the various signaling stations throughout the communication system the bidding on the particular lot of produce under consideration is known to have been terminated and 45 all of the parties are informed that the lot has been sold to the last bidder whose quotation has been transmitted over the teletypewriter system.

While the invention has been described in connection with certain specific embodiments to-

gether with certain particular uses to which the invention is adapted, it is to be understood that numerous variations will occur to those skilled in the art and it is intended that such modifications will be covered by the appended claims.

I claim:

1. In a selling control system of the character described for facilitating the sale of commodities by competitive bidding at a plurality of remotely located stations, the combination of a communication network connecting said stations, a transmitter and receiver at each station connected to the network, each transmitter having means for transmitting over the network impulse combinations representing bids and each receiver having means for visually indicating the bids corresponding to the impulse combinations, a signal device at each station for indicating by its operation that bids may be transmitted from the stations, means included in at least one of the transmitters for transmitting a selected impulse combination over the network indicative of the beginning of a bidding period, means at each station operated by either the transmitter or receiver thereat in response to the operation of the said transmitter when transmitting the selected impulse combination for operating the signal device thereat and means depending upon the transmitting over the network within predetermined intervals of another selected impulse combination by any one of the transmitters and the reception thereof at the other stations for sustaining the operation of the signal devices, whereby said signal devices will be maintained in operation if a succession of bids follow each other within predetermined intervals.

2. In a selling control system of the character described for facilitating the sale of commodities by competitive bidding at a plurality of remotely located stations, the combination of a communication system comprising a plurality of stations, a transmitter and receiver located at each station, each transmitter having means for transmitting over the system impulse combinations representing bids and each receiver having means for visually indicating the bids corresponding to the impulse combinations, a signal device at each station for indicating by its operation that bids may be transmitted from the stations, the transmitter in at least one of said stations comprising means for transmitting a selected impulse combination over the system indicative of the beginning of a bidding period, means located at each of the stations which receive said selected impulse combination operated by the selected impulse combination received thereat in response to the operation of the said transmitter when transmitting the selected impulse combination for operating the signal device and means depending upon the transmission over the system within predetermined intervals of another selected impulse combination by any one of the transmitters and the reception thereof at the other stations for sustaining the operation of the signal devices, whereby said signal devices at the stations will be maintained in operation if a succession of bids follow each other within predetermined intervals.

3. In a selling control system of the character described for facilitating the sale of commodities by competitive bidding at a plurality of remotely located stations, the combination of a communication system comprising a plurality of stations, a transmitter and receiver located at

each station, each transmitter having means for transmitting over the system impulse combinations representing bids and each receiver having means for visually indicating the bids corresponding to the impulse combinations, a signal device at each station for indicating by its operation that bids may be transmitted from the stations, the transmitter in at least one of said stations comprising means for transmitting a selected impulse combination over the system indicative of the beginning of a bidding period, means at each station receiving said selected impulse combination operated by the receiver thereat in response to the operation of the said transmitter when transmitting the selected impulse combination for starting the operation of the signal device, signal operation terminating means at each station serving to stop the operation of the signal device after a predetermined period of time, the operation of said signal operation terminating means being initiated upon the operation of the signal device and means depending upon the transmission over the system of another selected impulse combination by any one of the transmitters and the reception thereof at the other stations during the period the signal device is in operation for re-initiating the signal operation terminating means for another predetermined period of time whereby said signal devices at the stations will be maintained in operation if a succession of selected impulse combinations follow each other within predetermined intervals.

4. In a selling control system of the character described for facilitating the sale of commodities by competitive bidding at a plurality of remotely located stations, the combination of a communication system comprising a plurality of stations, a transmitter and receiver located at each station, each transmitter having means for transmitting over the system impulse combinations representing bids and each receiver having means for visually indicating the bids corresponding to the impulse combinations, a signal device at each station for indicating by its operation that bids may be transmitted from the stations, time delay means for stopping the operation of said signal device a predetermined time after said means have been initiated, the transmitter in at least one of said stations comprising means for transmitting a selected impulse combination over the system indicative of the beginning of a bidding period, means at each station operated by the selected impulse combination indicative of the beginning of the bidding period received at each of the stations in response to the operation of said transmitter for operating the signal device and initiating operation of said time delay signal stopping means to terminate the operation of the signal device after a predetermined time interval and means depending upon the transmission over the system during the operation of the signal device of another selected impulse combination by any one of the transmitters and the reception thereof at the other stations for reinitiating operation of the time delay signal stopping means in each of the stations, whereby said signal devices at the stations will be maintained in operation if a succession of selected impulse combinations follow each other within predetermined intervals.

5. In a selling control system of the character described for facilitating the sale of commodities by competitive bidding at a plurality of remotely located stations, the combination of a commun-

cation system comprising a plurality of stations, a transmitter and receiver located at each station, each transmitter having means for transmitting over the system impulse combinations representing bids and each receiver having means for visually indicating the bids corresponding to the impulse combinations, each of said receivers also having associated therewith at least two movable elements each of which is separately operable in response to pre-selected impulse combinations received over the system, a signal circuit located at each station comprising a signal device for indicating during its operation a period within which bids may be transmitted over the selling control system, means operated by 15 one of said movable elements upon reception by

5
10
15

the receiver of a pre-selected impulse combination for energizing said signal circuit to indicate the beginning of the bidding period, means for de-energizing said signal circuit after a predetermined elapse of time to indicate the termination of the bidding period, the operation of said de-energizing means being initiated upon the energization of said signal circuit and means effective only during the period of time the signal device is energized operated by a different movable element for re-initiating the operation of said de-energizing means whereby the signal circuit will remain energized for another predetermined period of time.

HARRY H. STOCKFELD.
